(57) **CLAIM**

The ornamental design for a display screen or portion thereof with transitional graphical user interface, as shown and described.

DESCRIPTION

FIG. 1 is a front view of a display screen or portion thereof with transitional graphical user interface showing a first image in a sequence showing our new design;

FIG. 2 is a second image thereof;

FIG. 3 is a third image thereof; and,

FIG. 4 is a fourth image thereof.

The appearance of the transitional graphical user interface transitions between the images shown in FIGS. 1 through 4. The process or period in which one image transitions to another forms no part of the claimed design.

The outermost dash-dot broken lines in the drawings illustrate the display screen or portion thereof and form no part of the claimed design. The dotted broken lines in the drawings illustrate portions of the graphical user interface that form no part of the claimed design.

1 Claim, 4 Drawing Sheets

Article Title

Text example: In the whole scene, the
grayscale of the font has the greatest
influence on font recognition and clarity.

Due to the size difference of devices, such
as TV and watch, the font size will be very
different. The display of large font size is
ok, but the small font size is difficult to
see. And differences in lighting conditions,
we know that TV is commonly used
indoors at night, weak brightness of word
recognition will be weaker, and car
machine is used in outdoors scene.
